R. M. BRENNER,
RACE GAME APPARATUS,
APPLICATION FILED DEC. 10, 1919.

1,346,697.

Patented July 13, 1920.

FIG. 1.

UNITED STATES PATENT OFFICE.

RICHARD M. BRENNER, OF PALISADE, NEW JERSEY.

RACE-GAME APPARATUS.

1,346,697.

Specification of Letters Patent. Patented July 13, 1920.

Application filed December 10, 1919. Serial No. 343,759.

To all whom it may concern:

Be it known that I, RICHARD M. BRENNER, a citizen of the United States, and a resident of Palisade, in the county of Bergen and 5 State of New Jersey, have invented a new and Improved Race-Game Apparatus, of which the following is a full, clear, and exact description.

The invention relates to race game apparatus, such as shown and described in the Letters Patent of the United States, No. 1,011,563, granted to me December 12, 1911, and No. 1,203,474, granted to me October 31, 1916.

15 The object of the present invention is to provide a new and improved race game apparatus for use in pleasure resorts, parks, exhibition grounds, and other places, and arranged to enable a number of players 20 simultaneously to manipulate racing objects, such as figures representing horses, for instance, with a view to cause such racing objects to travel over individual tracks thereby simulating a race, the winning of which is 25 solely dependent on the skill of the players.

Another object is to provide a race game apparatus which is exceedingly simple and durable in construction, and in which it requires but little physical exertion on the part 30 of the players to manipulate the racing tables on which the racing objects travel.

With these and other objects in view, the invention consists of certain novel features of construction, as hereinafter shown and described and then specifically pointed out in the claims.

A practical embodiment of the invention is represented in the accompanying drawings forming a part of this specification, in 40 which similar characters of reference indicate corresponding parts in all the views.

Figure 1 is a sectional side elevation of the race game apparatus;

Fig. 2 is an enlarged inverted sectional plan view of the rheostat, the section being on the line 2-2 of Fig. 1;

Fig. 3 is an enlarged sectional side elevation of the front end of one of the racing tables with the corresponding racing object 50 in circuit closing position, the circuit switch being of modified form; and

Fig. 4 is a plan view of the front end of the race game apparatus with the racing tables provided with the modified form of 55 closing switch.

On a suitably constructed frame or stand

10 is mounted a support 11, preferably in the form of a box having an open top provided with longitudinally extending partitions 12, dividing the open top into spaces 13 60 in which are mounted a plurality of longitudinally extending narrow racing tables 14, over which are adapted to travel racing objects 15, such as figures representing horses and jockeys or the like, as plainly indicated 65 in Figs. 1 and 3. The racing objects 15 start simultaneously from the rear right-hand ends of the tables 14 and finish at the forward left-hand ends of the said tables. The several tables 14 and the means for 70 moving the same forward and backward are alike, and it suffices to describe but one in detail. Each table 14 is supported on sets of parallel links 20 having their upper pivots 21 attached to the under side of the tables 75 14 while the lower pivots 22 engage longitudinally extending slots 23 formed in the partitions 12. The links 20 are adjusted so that they stand in an approximately vertical position at the time the table 14 is at 80 the end of its forward stroke, while the links 20 swing downward and rearward during the return stroke of the table so that on the forward stroke the table 14 moves forward and upward, and during the return 85 stroke moves downward and rearward. The racing objects 15 are so adjusted in weight that during the forward and upward stroke of the tables 14 they remain stationary on their tables, while during the downward and 90 rearward stroke the racing objects move forward from the starting end toward the finishing end.

The speed at which the tables 14 moves forward and backward is controlled by a 95 number of players corresponding to the number of the tables, so that each player controls the speed of a table and hence the result of the race depends solely upon the skill and judgment of each player for the 100 reason that if the player moves his racing table at too slow a speed the racing object will move forward too slowly to win the race while if the player moves his racing table too fast and becomes excited the racing objects are not liable to move forward at all but, owing to the excessive vibration created in moving the table too fast, commence to dance or fall and thus are taken out of the race. If the player intends to run the table 110 at an excessive speed its driving power is shut off and the table comes to a standstill.

In order to accomplish the desired result, the under side of each racing table 14 is provided near its forward end with a depending bracket 30 connected by a pitman 31 with a 5 wrist pin 32 held on a gear wheel 33, the shaft 34 of which is preferably journaled on the frame 35 of a motor 36, preferably of the electric type, and mounted on the bottom of the support 11. The gear wheel 33 is in 10 mesh with a gear wheel 37 secured on the shaft 38 of the motor 36 and hence when the motor is running the pitman 31 imparts a forward and backward traveling motion to the table 14. The wires 40 and 41 of the 15 electric motor 36 are connected with a battery 42 or other suitable source of electric energy, and a switch 43 is arranged in the wire 41 to open or close the circuit for the electric motor. The circuit wires 40 and 41 20 are also connected with a rheostat 50 having a plurality of fixed spaced contacts 51 and a movable contact 52 adapted to engage the fixed contacts 51 to gradually increase or decrease the speed of the motor according to 25 the direction in which the movable member 52 is moved at the time. The movable member 52 of the rheostat is in the form of a lever fulcrumed at 53 on a column 54, which also supports the rheostat 50, and the said 30 movable member 52 is provided with a shifting arm 55 engaging a collar 56 held on a sleeve 57 forming part of a governor 60. The governor 60 is mounted on a shaft 61 journaled at its lower end in the stand 54 35 and at its upper end in a bearing 62 arranged on a table 63 located in front of the support 11 and in front of which range the several players. Each of the players manipulates a crank disk 64 secured to the upper end of 40 the shaft 61 to rotate the latter at a desired speed. The governor 60 is provided with a head 65 secured to the shaft 61 and on the head 65 are pivoted the weighted arms 66 connected by the links 67 with the sleeve 57 45 to move the latter up or down according to the increase or decrease in the speed given to the shaft 61 by the player turning the crank disk 64 correspondingly. It will be noticed that normally the movable member 52 is at 50 the right hand side of the rheostat 50 and when the player turns the crank disk 64 then the governor 60 imparts a swinging motion to the movable member 52 of the rheostat to move the movable member 52 successively in engagement with the fixed contacts 51 thereby gradually increasing the speed of the motor. Now in case the player rotates the crank disk 64 at an excessive rate 55 of speed then the movable member 52 moves past the last contact 51 and hence the motor circuit is broken and the motor comes to a standstill.

In order to return the movable member 52 to starting position but without passing over the fixed contacts 51, use is made of a spring

guide arm 70 spaced from the fixed contacts 51 to allow the movable member 52 to pass in the rear of this guide, the left hand end 71 of which is in the form of a spring extending into the path of the movable member 52 so that when the latter moves into extreme left hand position it passes under the spring end 71, lifts the same, and then passes out of engagement with it to allow the spring end 71 to return to closed position, 75 as shown in Fig. 2. Now on moving the movable member 52 from the left to the right it passes up the spring end 71 and along the guide 70 without touching the fixed contacts 51. It is understood that when the 80 crank disk 64 is turned at an excessive rate of speed the movable member 52 moves beyond the last fixed contact 51 on the left hand side of the rheostat 50 and hence the motor circuit is broken and the motor 36 comes to a standstill and remains so until the speed of the crank disk 64 is reduced and practically stopped to allow the movable member 52 to return to starting position and to again close the motor circuit on restarting 85 the crank disk 64.

The motor circuit is broken automatically on a racing object 15 reaching the goal at the forward end of the racing table 14. For this purpose the forward end of each racing 90 table 14 is provided with two contacts 80 and 81, of which the contact 80 is in the form of a spring column out of engagement with the contact 81 and adapted to be pressed in contact with the same on the base 95 82 of the racing object traveling up the spring contact 80 and forcing the same downward into engagement with the contact 81. The contacts 80 and 81 are connected with circuit wires 83, 84 connected with a battery or other suitable source of electrical energy 85 and the said circuit wires 83, 84 connect with an electromagnet 90, the armature 91 of which forms a switch in the circuit wire 41 of the motor circuit, as 100 plainly shown in Fig. 1. The armature switch 91 is normally closed but when the racing object 15 presses the spring contact 80 into engagement with the contact 81 then the electric circuit for the electromagnet 110 90 is closed and the latter is energized and attracts the switch armature 91 thus breaking the circuit for the motor 36. The latter is now stopped and the corresponding racing table 14 comes to a standstill. The electric circuit for the electromagnet 90 of each racing table 14 connects with an annunciator 92 of any approved construction, and hence the latter indicates the number of the winner of the race, it being understood that 115 the number corresponds to the number on the corresponding operating crank disk 64. Instead of a spring contact 80 use may be made of two spaced contacts 95, 96 arranged in a block 97 of insulating material and set 120 130

in the front end of the racing table 14, as plainly shown in Figs. 3 and 4. It will be noticed that when the racing object 15 is moving into winning position on the forward end of its racing table, then its base 82 spans both contacts 95, 96 thus closing the circuit for the electromagnet 90 and the annunciator 92.

It is understood that in running the apparatus, the racing objects 15 are placed on the starting end of the racing tables 14 and then the individual players turn their crank disk 64 to start the electric motors 36 and to run the same at a higher or lower speed according to the speed with which the crank disks 64 are turned. The running of each motor 36 causes a corresponding forward and backward movement of the corresponding racing table 14 with a view to move the racing objects 15 intermittently forward, and when the racing object reaches the goal at the forward end of the racing table 14 it closes the circuit for the electromagnet 90 whereby the motor circuit is broken and the motor comes to a standstill thus preventing further movement of the racing table 14 and of the racing object 15 thereon. It will also be noticed that when the racing object 15 reaches the goal the corresponding number is displayed by the annunciator 92 thus indicating the winner of the race.

In order to prevent non-players from actuating the racing table 14, use is made of a bridging wire 100 spanning the wire 84 adjacent the contacts 80 and 81, and in this bridging wire 100 is arranged a switch 101 normally open to allow of proper action of the racing game apparatus, as above described. The circuit wires 83, 84 are connected with an electromagnet or solenoid 103 having its core 104 connected with a shifting lever 105 engaging a collar 106 forming part of the governor sleeve 57 of the governor 60. After a race is run the racing objects 15 are returned to starting position and in order to prevent non-players from actuating the racing tables 14 prior to starting the next race, the attendant closes the switch 101 whereby the electromagnet 103 is energized and hence the governor 60 is actuated and moved into high speed position. By the movement of the governor 60 the movable member 52 is moved past the last contact 51 and is held in this position until the switch 101 is moved back into open position. It will be noticed that the movable member 52 of the rheostat 50 is rendered inactive even should a non-player turn the crank disk 64 during the time the switch 101 is closed.

Having thus described my invention, I claim as new and desire to secure by Letters Patent:—

1. An amusement apparatus, comprising a racing table, a racing object adapted to

travel on the said racing table, a motor connected with the said racing table to move the same forward and backward, and a motor controlling device adapted to be actuated by a player and connected with the said motor to govern the speed thereof and hence the forward and backward movement of the said racing table. 70

2. An amusement apparatus, comprising a racing table, a racing object adapted to travel on the said racing table, a motor connected with the said racing table to move the same forward and backward, the said motor being of the electrical type, a rheostat in the circuit of the said motor and having 80 a movable member, and a controlling device under the control of a player and connected with the said movable member of the rheostat to vary the speed of the motor and the movement of the said racing table. 85

3. An amusement apparatus, comprising a racing table, a racing object adapted to travel on the said racing table, a motor connected with the said racing table to move the same forward and backward, the said 90 motor being of the electrical type, a rheostat in the circuit of the said motor and having a movable member, a controlling device under the control of a player and connected with the said movable member of the rheostat to vary the speed of the motor and the movement of the said racing table, and means adapted to be engaged by the said movable rheostat member to hold the latter inoperative while returning it to starting 100 position.

4. An amusement apparatus, comprising a racing table, a racing object adapted to travel on the said racing table, a motor connected with the said racing table to move the same forward and backward, the said motor being of the electrical type, a rheostat in the circuit of the said electric motor and having a plurality of fixed contacts and a movable contact member adapted to engage 105 the said fixed contacts, a shaft adapted to be turned by a player, and a governor on the said shaft and connected with the said movable rheostat member. 110

5. An amusement apparatus, comprising 115 a racing table, a racing object adapted to travel on the said racing table, a motor connected with the said racing table to move the same forward and backward, the said motor being of the electrical type, a rheostat 120 in the circuit of the said motor and having a movable member, and a controlling device under the control of a player and connected with the said movable member of the rheostat to vary the speed of the motor and the 125 movement of the said racing table, and a controlling device under the control of the attendant of the apparatus and connected with the said controlling device to hold the said movable member in inactive position. 130

6. An amusement apparatus, comprising a racing table, a racing object adapted to travel on the said racing table, a motor connected with the said racing table to move the same forward and backward, the said motor being of the electrical type, a rheostat in the circuit of the said electric motor and having a plurality of fixed contacts and a movable contact member adapted to engage 5 the said fixed contacts, a shaft adapted to be turned by a player, a governor on the said shaft and connected with the said movable rheostat member, and an electric controlling device under the control of the attendant 10 of the apparatus and connected with the said governor to hold the said movable member in inactive position.

7. An amusement apparatus, comprising a racing table, a racing object adapted to 20 travel on the said racing table, a motor connected with the said racing table to move the same forward and backward, the said motor being of the electrical type, a rheostat in the circuit of the said electric motor and having a plurality of fixed contacts and a 25 movable contact member adapted to engage the said fixed contacts, a shaft adapted to be turned by a player, a governor on the said shaft and connected with the said movable rheostat member, an electric controlling 30 device having an electric circuit provided with a normally open switch under the control of the attendant of the apparatus, the said electric controlling device being connected with the said governor to move the 35 latter into high speed position on the attendant closing the said switch.

8. An amusement apparatus, comprising a racing table, a racing object adapted to 40 travel on the said racing table, a motor connected with the said racing table to move the same forward and backward, the said motor being of the electrical type, a rheostat in the circuit of the said electric motor and having a plurality of fixed contacts and a 45 movable contact member adapted to engage the said fixed contacts, a shaft adapted to be turned by a player, a governor on the said shaft and connected with the said movable rheostat member, and a returned guide 50 for the said movable rheostat member to hold the latter out of engagement with the said fixed contacts during the return movement of the said movable rheostat member

from an outer end position to a starting 55 position.

9. An amusement apparatus, comprising a racing table, a racing object adapted to travel on the said racing table, a motor connected with the said racing table to move 60 the same forward and backward, the said motor being of the electrical type, a rheostat in the circuit of the said motor and having a movable member, a controlling device under the control of a player and connected 65 with the said movable member of the rheostat to vary the speed of the motor and the movement of the said racing table, an electric annunciator having an electric circuit independent of the said motor circuit, and 70 an electric switch for the said annunciator circuit and controlled by the said racing object.

10. An amusement apparatus, comprising a racing table, a racing object adapted to 75 travel on the said racing table, a motor connected with the said racing table to move the same forward and backward, the said motor being of the electrical type, a rheostat in the circuit of the said motor and having a 80 movable member, a controlling device under the control of a player and connected with the said movable member of the rheostat to vary the speed of the motor and the movement of the said racing table, an electric annunciator having an electric circuit independent of the said motor circuit, an electric switch for the said annunciator circuit and controlled by the said racing object, and an 85 electromagnet in the said annunciator circuit 90 and having its armature forming a switch for the said motor circuit to break the latter and stop the motor on the racing object closing the annunciator circuit.

11. An amusement apparatus, comprising 95 a racing table, a racing object adapted to travel thereon, an electric motor, means connecting the electric motor with the said racing table to impart a forward and backward movement to the racing table, means controlled by an operator for controlling the speed of the motor, a normally closed switch in the motor circuit and an electric device controlling the said switch and controlled by the racing object on reaching the forward end of the racing table.

RICHARD M. BRENNER.
